UNITED STATES PATENT OFFICE.

CHARLES G. RUBY, OF BEACON, IOWA.

CAR-COUPING.

SPECIFICATION forming part of Letters Patent No. 425,001, dated April 8, 1890.

Application filed January 10, 1890. Serial No. 336,491. (No model.)

To all whom it may concern:

Be it known that I, CHARLES G. RUBY, a citizen of the United States, residing at Beacon, in the county of Mahaska and State of Iowa, have invented certain new and useful Improvements in Car-Couplings; and I do declare the following to be a full, clear, and exact description of the invention, such as will enable others skilled in the art to which it app pertains to make and use the same.

This invention has relation to an improvement in devices for coupling cars; and it has for its object to provide means whereby cars may be automatically coupled and uncoupled without necessitating the objection of going between the cars, the coupling-bar being adapted to serve with a draw-head having the ordinary coupling-pin, and also a draw-head having locking-jaws.

The invention will be fully understood from the following description and claim, when taken in connection with the annexed drawings, in which—

Figure 1 is a perspective view of my improved coupling device attached to a portion of a car with the coupling link or bar in position. Fig. 2 is a longitudinal sectional view of a draw-head with my improvements therein, and Fig. 3 is a view of the operating-shaft and ratchet-wheel removed from the draw-head.

Referring by letter to the said drawings, A indicates a draw-head, which may be of any ordinary or approved construction, having sufficient internal space for the lateral movement of the locking-jaws, as will be presently explained. This draw-head is also provided at a suitable point with a vertical aperture a, which is designed to receive a coupling-pin.

B indicates two similar locking-jaws. These jaws are of a form substantially as shown, and arranged entirely within the draw-head, being pivoted therein near their rear ends, as shown at b.

The jaws B are tapered on their rear inner sides from the pivotal point outwardly and rearwardly, as shown at c, and interposed between these tapered portions is a spiral or other suitable spring D, which bears at its opposite ends against the inner sides of the beveled or tapered portions, and said spring is sustained in position by a horizontal rod e,

which passes through the spring and also through apertures in the jaws. The opposite or forward ends of these jaws are beveled in the ordinary manner, to conform with the bevel of the coupling link or bar, and have shoulders f to engage similar shoulders on the coupling link or bar, whereby said link may be held within the draw-head.

E indicates the coupling-link. This link is provided on opposite ends with an arrow-head, and such heads are also provided with apertures g, so that they may serve in connection with the spring-actuated jaws or the ordinary coupling-pin.

Arranged in rear of the pin-aperture in the draw-head is the vertical shaft F, having at its upper end a hand-wheel or other device, whereby said shaft may be turned, and this shaft, which passes vertically through the draw-head, has fixed to it a ratchet-wheel G, which is designed to operate in connection with a pivoted pawl h, which is backed by a spring i.

K indicates a horizontal lever which is arranged within the draw-head between the jaws thereof, and is made fast to the shaft F, whereby it may be made to turn as the shaft has been partly rotated. This lever K, which is pivoted midway of its length, is designed, when turned in a transverse plane with respect to the draw-head, to engage the inner sides of the jaws B and move the same laterally, thereby disengaging the forward ends from the shoulders of the coupling-link and allowing the cars to uncouple.

The shaft F may be extended to the top of a box-car, so that the coupling may be operated from that point, and it is obvious that a rod may be extended to the side of a car, so that the shaft may be operated by a person standing on the ground without going between the cars.

From the position of the pawl and ratchet it will be seen that the shaft is always in a position to turn the lever and throw out the jaws; but in some cases, where a coupling-link of different form is used and the ordinary coupling-pin employed, it is desirable to have the jaws remain out, and in such cases it is simply necessary, after turning the lever in a transverse position, to allow the pawl to engage the ratchet-wheel. The coupler may

then be used with another car carrying the ordinary coupling link and pin.

I am aware that it is not new to provide a coupler with pivoted spring-actuated jaws, 5 and employ a rotative shaft with a ratchet and connect the shaft with the jaws by means of chains.

I am also aware that a lever secured to a rotative shaft has been employed for opening 10 the jaws.

Having described my invention, what I claim is—

The combination, with a draw-head having a pin-aperture, of a vertical rotative shaft 15 journaled therein, a horizontally-arranged le-

ver fixed to the lower end of the shaft within the draw-head, a ratchet fixed to the shaft above the draw-head, the jaws pivoted in the head and having their inner rear ends beveled, as at *c*, the rod *e*, passing through the 20 beveled portions of the jaws in rear of their pivotal points, and the spiral spring *D*, surrounding the rod and acting against the jaws, substantially as specified.

In testimony whereof I affix my signature in 25 presence of two witnesses.

CHARLES G. RUBY.
